UNITED STATES PATENT OFFICE

URBANO PINEDA, OF SEATTLE, WASHINGTON

DESIGN FOR A COMBINATION INKSTAND AND WRITING IMPLEMENT

Application filed July 15, 1930. Serial No. 36,360. Term of patent 3½ years.

To all whom it may concern:

Be it known that I, URBANO PINEDA, a citizen of the United States, residing at Seattle, in King County, and State of Washington, have invented a new, original, and ornamental Design for a Combination Inkstand and Writing Implement, of which the following is a specification, reference being had to the accompanying drawing, forming part thereof.

The figure is a perspective view of the inkstand, showing my new design.

I claim:

The ornamental design for a combination inkstand and writing implement, as shown.

URBANO PINEDA.
